 Filed Jan. 27, 1964, Ser. No. 340,405
 3 Claims. (Cl. 10—89)

The present invention relates to a pipe working apparatus or machine and in particular to an apparatus for cutting, threading and connecting large diameter pipes and fittings which is generally difficult when done manually.

The primary object of the invention is to provide an apparatus in which one end of a long section of pipe or cylindrical work piece may be held and rotated and the opposite end is rotatably held in position so that a pipe cutter, threader or fitting may be held in a stationary position for cutting, threading or screwing up fittings and smaller sections of pipe.

Another object of the invention is to provide an apparatus of this nature which may be easily and conveniently dismantled for erection in new locations when a new location is warranted.

A further object of the invention is to provide such an apparatus having certain parts collapsible and other parts removable in order that the apparatus may be conveniently handled and transported.

While several objects of the invention have been pointed out, other objects, uses and advantages of the invention will become more apparent as the nature of the invention becomes more fully disclosed and the same consists in the novel construction, combination and arrangement of parts shown in the accompanying drawings forming a part of this specification and in which:

FIGURE 1 is a plan view of the apparatus.

FIGURE 2 is a view in side elevation of the pipe handling apparatus as shown in FIGURE 1.

FIGURE 3 is a sectional view of the apparatus taken along line 3—3 of FIGURE 2.

FIGURE 4 is an enlarged elevational view of one of the elements of the apparatus.

FIGURE 5 is an enlarged plan view of one form of support for one of the elements of the apparatus taken on line 5—5 of FIGURE 2.

FIGURE 6 is an enlarged end view of the apparatus looking from left to right from the line 6—6 of FIGURE 2.

FIGURE 7 is an enlarged fragmentary sectional view in elevation of the elements C taken on line 7—7 of FIGURE 5.

FIGURE 8 is an enlarged fragmentary sectional view of the element C taken on line 8—8 of FIGURE 5.

FIGURE 9 is a fragmentary detailed sectional view of the locking element shown in FIGURE 8 for the supporting means E for carrying the element B.

FIGURE 10 is a section taken on line 10—10 of FIGURE 9.

FIGURE 11 is a fragmentary vertical view of one end of the apparatus showing the element C folded in a parallel plane with the track.

In referring to the illustrations, like numerals are used and point out like and similar parts throughout the several views.

The invention is preferably referred to as an apparatus for handling pipe, but may be referred to at times as a machine for the same purpose. The apparatus is provided with a track A having two rails 12 and 14. The rails are spaced apart and parallel with each other and extend the full length of the apparatus. Each rail is provided with a vertical portion and inwardly inclined horizontal flanges 16, 17, 18 and 19. The tracks 12 and 14 are held in parallel relationship by the ties 20, 21, 22, 23

2

and 24 which are preferably welded to the rails. However, they may be bolted or riveted if desired.

The rails and the tie members may be supported upwardly at a convenient height by the legs 25 which are braced by the cross-tie members 26 and 27 and laterally by tie members 28 and 29. These legs and braces are preferably held together and to the rails by bolts 30, in order that they may be removed from the rails when it is desired to move the apparatus.

10 Movable along the track adjacent one end thereof is a vise unit B having means for holding and rotating a chuck 32. The chuck 32 is provided with a short shaft 33' which is held in the rotatable vise unit B by any of the conventional means, such as, radially movable jaws. In 15 this arrangement different size chucks having the same size shafts may be conveniently interchanged in the same vise for holding the end of different size pipe, or cylindrical work piece. The chuck is provided with engaging means 33 for engaging one end of the pipe, or work piece 20 for rotating the same to perform work thereon, such as, cutting a thread on the opposite end thereof by a stationary threading tool as shown at 69. The thread is cut by placing the die tool over the outer end of the pipe allowing the tool handle 69' to rest on a stationary member 37 to keep the tool from rotating with the pipe. As 25 the pipe is rotated, it moves into the tool which cuts the thread.

The member 37 is preferably supported by having it 30 slidably receivable within a hollow tube 38 and may be adjusted longitudinally of the track to take care of the tool being used on the outer end of the pipe 34.

If the pipe is of some length it is most desirable to hold the center portion up in a line with the pipe engaging jaws, which will be referred to later.

Adjacent the end of the track opposite the vise unit B, is a pipe rest C shown in FIGURES 1, 2, 3, 4 and 6. The pipe rest is for supporting the outer end 34' of the pipe 34 and for holding it in position while it is rotated by the rotatable vise jaws 32. The outer end 34' of the pipe 34 is normally extended a short distance through and beyond the pipe rest C when a thread is to be cut thereon, the threading die 69 being positioned adjacent the rest. If the die is too far from the rest the pipe will spring and the thread may possibly be ragged and not cleanly cut.

The pipe rest C is provided with an opening and may be mounted to the track in any suitable manner. In the drawings (see FIG. 6) the rest is shown supported upon a tube 42 which in turn is mounted on the rails 12 and 14 by means of the pillow blocks 44 and 46. The rest C is formed in two parts 40 and 40' and is hingedly held on one side by the pin 41 and on the opposite side by a latch 43, which is normally operated by the extension arm 43'. The latch 43 is adapted to engage the portion 40'' to hold the same in engagement with the portion 40''. The portion 40 of the rest is provided with adjustable screws 48 and 48' and the portion 40' is provided with adjustable screws 49 and 49'. These screws are substantially evenly spaced about the rest C and are radially disposed therein. The inner end of the screws 48, 48', 49 and 49' rest against the outer surface of leaf springs 45, 45', 47 and 47'. One end of each of the springs is secured to the inner surface of the opening in the rest C by screws or bolts 45''. The inner end of the screws engage the outer surface of the springs adjacent their unattached ends. The unattached ends of each of the springs are turned upwardly to form lips 45''' in order that the pipe, or the work piece 34 may be freely rotated in either direction without fear of the pipe becoming engaged with the inner ends of the springs. The split rest also provides a means for opening up the rest

for conveniently laying the pipe vertically onto the rest. The rest is held to the tube 42 by a bracket 51 and 51' to which is attached collars 50 and 50' and is held in position by a screw 52 carried by a brace 53. The screw 52 is adapted to have its inner end 52' engage the tube 42 for securing the rest in place. The rest may be lowered to a horizontal position when moving the apparatus to prevent damage to the rest and for more convenient handling, as shown in FIGURE 11.

The rotatable vise at the opposite end of the track is preferably reversible and is operated at a very low speed through a gear chain (not shown) from any well known power source.

The support D is for supporting the center portion of long lengths of pipe between the rotating jaws 32 and the rest C. This support is likewise supported on a tube 55, similar to rest C. The tube 55 is supported on the track rails by having the ends of the tube welded to plates 56 and 57 carried at each end of the tube. These plates slide along the flanges 17 and 19 of the rails 14 and 12 respectively, and allows the support to be positioned at any convenient place along the track. The pipe support D is carried in a bracket 58 having an opening 59 for receiving a tube like portion 60 of the support. The portion is held in position by a screw 61 which may be tightened on the portion 60 at the desired height of the support. The upper end of the support is provided with V members 62 and 63 to form a cradle to receive the pipe. The V members are also provided with rollers 62' and 63' for allowing the pipe to be more easily rotated. The bracket 58 is also provided with a second opening 64 formed at right angles to the opening 59. This second opening is for engaging the tube 55 and is held in position thereon by a screw 65. This support may also be rotated about the tube 55, by loosening the screw 65 to place it in a position parallel with the track, such as that described for the rest C, to prevent any damage to it and for convenience in moving and storing of the apparatus.

Referring again to the vise unit B comprising the rotatable jaws and the rotating means for rotating the jaws are all preferably mounted to be movable along the track and is normally positioned at one end thereof and at the opposite end of the track from the rest C. This vise unit B is illustrated as being supported upon a table, or framework E, shown best in FIGURE 5. The table E is provided with holes 70 for attaching the vise unit thereto by suitable bolts 71. However, any other convenient means may be used if desired, such as, by welding. The table E is provided with side supporting members 72 and 74 extending along each side thereof. Rotatably attached to the supporting members 72 and 74 are rollers or wheels 75, 76, 77 and 78. The rollers or wheels 75 and 76 are rotatably carried at one end of the table on fixed axles 79 and 80. These rollers or wheels are adapted to run along the upper surfaces of the flanges 17 and 19 of the rails 12 and 14. Rollers or wheels 77 and 78 are rotatably supported on the axles 81 and 82. These axle members are adapted to be movable laterally to cause the wheels 77 and 78 to engage the rails and act as a brake to the carriage for holding the same in a predetermined position along the track. The braking action is accomplished by having the inner ends of the axles 81 and 82 threaded with right and left threads as shown at 81' and 82'. Suspended from the table is a bracket 83 into which is rotatably mounted an elongated element 84. This element 84 is provided with a wheel 85 fixed about its circumference for rotating the same within the bracket 83. The element 84 is provided with a horizontal threaded opening of a right and left hand thread, to receive the similar thread carried by the inner ends of the axle members 81 and 82. The wheels are held adjacent the ends of the respective axle member by a fixed collar, similar to the one shown at 86 in FIGURE 9. By this arrangement when the wheel 85 is rotated

in one direction the rollers or wheels 77 and 78 will be moved laterally to engage the rails and fix the position of the carriage relative to the track. When the wheel 85 is moved in the opposite direction, the axles are moved inwardly bringing the wheel to a point where they will roll along the upper surfaces of the flanges 17 and 19 without any excess friction with the remainder of the rail. However, if desired only one of the wheels 77 or 78 may be moved laterally to brake the carriage by having only one of the axles 81 or 82 movable by the rotating element 85 and the other axle stationary.

In use as a thread cutter, the rest C is first set upright, if not already in this position. The rest is then opened and the pipe is laid into the rest and the V shaped center support D. The end of the pipe adjacent the vise is inserted into the rotatable jaws and secured thereto by the elements 33. The rest C is then closed and latched and if not already adjusted, the screws 48 to 49' are adjusted for rotatably supporting that particular diameter pipe. At this point the support D is adjusted to its proper height to support the center of the pipe. After the pipe has been placed into operating position, a thread cutter die 69 is placed over the end of the pipe and the handle 69' is positioned to rest against the element 37, after which, the jaw rotating means is set in operation. The rotating means rotates the pipe which causes it to feed into the threading tool, thereby cutting the thread on the outer end of the pipe. When the thread has been sufficiently cut, the driving means for the jaws is reversed to remove the die from the pipe, or the member 37 may be pushed back into the member 38 to allow the handles 69' of the threading tool to be swung about, whereby the threading die may be manually removed from the end of the pipe when the rotatable jaws are stopped.

The rotating means is shown as an electric motor but may be of any desirable power unit, such as, an engine of any kind.

The apparatus has a number of uses, that is, it is used to assist in cutting pipe in various lengths, by substituting a pipe cutter for the thread cutting tool, also sections of pipe and fitting may be assembled as shown in FIGURE 2, whereby several lengths of shorter pieces of pipe may be screwed into a fitting 35 or screwed together. The various sections of pipe and the fitting may be held in position by attaching to the pipe a pipe wrench and allowing the wrench handle to bear against the member 37 or the track rail to hold the wrench from rotating.

While a table E has been shown and described in detail for supporting the vise unit, other suitable means may be substituted, such as, using the base of the vise unit itself by extending its base or supporting feet B' and B'' to the rails and supporting the vise unit directly thereon, or by spacing the rails at such distance as to accommodate the feet B' and B''. The vise B may also be supported on the rails by individual attachments such as slides or rollers carried by the feet.

The apparatus is primarily for use in installations in which large diameter pipe is used and is adapted to be set up on the premises upon the demountable frame, comprising the legs 25 and the bracing members 26, 27, 28 and 29 which are bolted together by the bolts 30. When the apparatus is moved the vise unit B may be removed from the tracks and the rest C and support D folded parallel with the rails which makes the handling of the apparatus lighter, easier and more convenient.

While the invention has been shown and described in detail, it is not intended as a limitation as the scope of the invention is best defined in the appended claims.

We claim:

1. A machine for supporting and rotating cylindrical work pieces having means for engaging one end of the cylindrical work piece and a rest for rotatably supporting the opposite end of the said work piece wherein the rest comprises; a closable casing having an opening therethrough, a plurality of leaf springs having one end of

each of the springs attached adjacent the inner surface of the opening through the casing, the opposite ends of the said springs extending inwardly toward the center of the opening and being radially movable relative to the center of the opening, means carried by the casing adapted to engage said opposite end of the leaf springs for adjustable limiting at least their outward movement.

2. A pipe handling apparatus comprising, in combination:

- (a) an elongated track consisting of two spaced parallel corresponding rails, each of the rails having a vertical portion and horizontal parallel flanges extending along the adjacent surfaces of the vertical portions of said rails; 10
- (b) a vise having rotatable jaws for supporting one end of the pipe and means for rotating said jaws; 15
- (c) means adjacent one end of the track for movably supporting the said vise along the said track;
- (d) said vise supporting means comprising a carriage provided with rollers adjacent its outer lateral edges for rotatably engaging a single flange of each of the rails of said track;
- (e) a fixed rest adjacent the opposite end of the track 20

having an opening therethrough for rotatably supporting the opposite end of the pipe within said opening when rotated by the jaws to perform work on the pipe.

- 5 3. A pipe handling machine as claimed in claim 2 having means for preventing the rotation of at least one of the said rollers to provide a brake for the carriage.
